(57) **CLAIM**

I claim the ornamental design for a tripenta wrench, as shown
and described.

DESCRIPTION

FIG. 1 is a perspective view of a tripenta wrench, showing my
design;

FIG. 2 is a front elevational view of the tripenta wrench of
FIG. 1;

FIG. 3 is a rear elevational view of the tripenta wrench of FIG.
1;

FIG. 4 is a right side elevational view of the tripenta wrench
of FIG. 1;

FIG. 5 is a left side elevational view of the tripenta wrench of
FIG. 1;

FIG. 6 is a top view of the tripenta wrench of FIG. 1; and,
FIG. 7 is a bottom view of the tripenta wrench of FIG. 1.
